Primary Examiner — Mary Ann Calabrese(74) *Attorney, Agent, or Firm* — NSIP Law**CLAIM**

The ornamental design for a display screen or portion thereof with graphical user interface, as shown and described.

DESCRIPTION

FIGURE is a front view of a display screen or portion thereof with graphical user interface showing my new design. In the drawings, broken lines showing a display screen, mobile terminal, text, letters, numbers, and symbols illustrate environment and form no part of the claimed design.
